UNITED STATES PATENT OFFICE.

RICHARD EDWARD CALLAHAN, OF TORONTO, ONTARIO, CANADA.

DISHWASHING MACHINE.

Application filed January 21, 1921. Serial No. 438,943.

To all whom it may concern:

Be it known that I, RICHARD EDWARD CALLAHAN, a citizen of the United States of America, and resident of 24 King St. west, 5 in the city of Toronto, in the county of York, in the Province of Ontario, in the Dominion of Canada, have invented certain new and useful Improvements in Dishwashing Machines, of which the following is a 10 specification.

The invention relates to improvements in dish washing machines as described in the present specification and shown in the accompanying drawings that form a part of 15 the same.

The invention consists essentially of the novel construction and arrangement of parts whereby a dish rack is supported on a vertical spindle arranged centrally thereof and 20 suitably geared to rotate said dish rack in the path of the cleaning fluid.

The objects of the invention are to eliminate the annoyance and discomfort consequent upon the washing of dishes by the 25 present method, which necessitates placing the hands in the water, to provide a dish washing machine particularly adapted for use in private homes and other like places, and generally to produce a dish washing 30 machine which will be inexpensive of construction, simple of operation, durable and efficient.

In the drawings Figure 1 is a vertical sectional view through the device in its assembled condition, the raised position of the lid being shown in dotted lines.

Figure 2 is a vertical sectional view taken on the line A—A of Figure 1.

Figure 3 is a plan view of the machine.

Figure 4 is a plan view of the fan employed to agitate the water.

Figure 5 is a plan view showing the container for the dishes, in its open position.

Figure 6 is a side elevation of the fan 45 shown in Figure 4.

Like numerals of reference indicate corresponding parts in the various figures.

Referring to the drawings 1 is the enclosing casing, the particular shape of which 50 does not form a part of the present invention but for purposes of illustration is shown as being of cylindrical form and being provided with a pedestal 2.

3 is the closure for the casing or container 1, said closure being hinged as at 4 to said 55 casing and being provided with a catch 5 located substantially opposite to the hinges 4 and adapted to register with a suitable fastener 6, secured to the side wall of said container.

7 is the motor which may be secured in any desired manner to the outer side of the lid 3 and to which is operatively connected a bevel gear 8, said bevel gear being adapted to project downwardly through an opening 65 in said lid for the purpose of operatively engaging gearing located within the container as will be explained hereinafter.

9 is the dish rack or container comprising a pair of sections each substantially 70 semi-circular in plan, hingedly secured together along corresponding sides as at 10 and at their opposite sides being provided with means, indicated by the numeral 11 for locking the sections together to form a cylindrical container, said container being of reticular construction and being provided with shelves 12, of which there may be any desired number, for the purpose of supporting the dishes or other articles to be washed.

The rack or container 9 is of smaller dimensions than the outer casing 1 and is adapted to be rotatably supported within said outer casing by means of a spindle 13 extending longitudinally through the centre 75 of said rack and keyed to one of the sections thereof, one end of said spindle being provided with a conical bearing 14 therein adapted to receive the cone shaped end of a supporting member 15 rigidly secured centrally of the bottom of the casing 1, and the other end of said spindle being formed with

cone shaped end 16 adapted to enter a correspondingly shaped opening in a block 17 rigidly secured on the under side of the lid 80 3, centrally thereof. As the block 17 is carried by the lid 3 it is apparent that the spindle 13 will tilt from a true vertical position

when said lid is raised and it is therefore essential that means be provided for automatically entering said spindle coincident with the closing of said lid and for this purpose the end of said block is concaved as at 18 from the centre of which concavity 85 extends the bearing for the spindle, so that 100 upon the closing of the lid the concaved

105

surface of said block will engage the pointed end of the spindle and guide same into its bearing.

19 is a bevel gear horizontally mounted 5 on the spindle 13 above the dish rack and keyed to said spindle and being adapted to mesh with the gear 8 when the lid 3 is closed so that upon the starting of the motor 7 the spindle 13 carrying the dish rack will be 10 rotated on its bearings.

20 is a comparatively shallow cone shaped fan having a central sleeve 20^a keyed to the spindle 12 below the rack 9 and having portions of the surface thereof punched up- 15 wardly to form blades 21 located at intervals therearound, said fan being for the purpose of splashing the water upwardly into the dish rack as well as forming a support for the spindle 13 upon the raising of the lid 3.

20. The water is sprayed into the dish rack 9 by means of a pipe or nozzle 22 vertically arranged within the outer casing 1 and having perforations 23 throughout its length, said pipe being connected to the supply pipe 25 24 by means of a bifurcated pipe 25 inter- posed therebetween, the branches 26 and 27 of said pipe being preferably provided with a central web 28 and lateral extensions 29 therefrom, to the latter of which may be se- 30 cured in any desired manner a soap receptacle 30, said branch 26 being cut away on its underside to afford open communication with the interior of said soap receptacle.

31 and 32 are valves adapted to control 35 the supply of water to the branches 26 and 27 respectively.

33 is an outlet pipe communicating with the interior of the outer casing 1 and controlled by a valve 34.

40. In the use of this invention the lid 3 is first raised, disengaging the gears 8 and 19 and releasing the upper end of the spindle 13 from its bearing in the block 17, thus permitting of the withdrawal, through the 45 top of the outer casing, of the dish rack 9, including of course the gear 19, the spindle 13 and the fan 20, the latter forming a means for supporting the dish rack in a vertical position while removed from its 50 bearing in the casing 1. The fastening means 11 is then released and the container 9 opened to permit of the dishes or other articles being placed on the shelves 12 after which said container is closed and replaced 55 within the casing and the lid 3 closed and fastened, the concaved lower face of the block 17 guiding the end of the spindle 13 to bearing in said block, causing the gears 8 and 19 to mesh. The dish rack is then set 60 in motion through the starting of the motor 7 and the water is turned on preferably first by means of the valve 31 as the opening of this valve permits of the water reaching the nozzle 22 through the pipe 26, which pipe 65 is in open communication with the soap box

30, thus first spraying the dishes with a soapy solution. As the water drops from the dish rack it falls on to the swiftly re- 70 volving fan which splashes it upwardly again into contact with the dishes in the rack. When sufficient of the soapy solution has been sprayed into the dish rack the valve 31 may be closed and the valve 32 opened thus releasing the clear water through the branch 27 of the pipe 25 after which said 75 valve 32 may be closed and the outlet valve 34 opened to permit of the draining of the casing 1. The lid 3 is then opened and the rack 9 withdrawn as described hereinbefore and the dishes removed for drying. 80

While I have thus described the preferred construction combination and arrangement of parts which constitute the present invention, it is obvious that others skilled in the arts of which this appertains, may make 85 various changes without departing from the spirit and scope of the invention as contained in the claims for novelty following.

What I claim is:—

1. In a dish washing machine, a casing, 90 having an opening at the top end thereof, a closure for said opening, a dish rack rotatably supported within said casing, means for rotating said dish rack, a nozzle supported between said rack and said casing and connecting with the source of water supply and discharging into said rack, and means rotatable with said rack and receiving the drip therefrom for splashing same into said rack. 100

2. In a dish washing machine, a casing, having an opening at the top end thereof, a closure for said opening, a dish rack in reticular form rotatably supported within said casing and withdrawable through said 105 opening, means for rotating said rack, a nozzle supported between said rack and said casing and connected with the source of water supply and discharging into said rack, and a convex member positioned below said 110 dish rack and rotatable therewith and carrying blades adapted to return the drip form said dish rack.

3. In a dish washing machine, a casing having an opening at the top end thereof, a 115 closure for said opening, a dish rack in reticular form rotatably supported within said casing and removable through the top end thereof, means for rotating said dish rack, a nozzle supported between said rack and said 120 casing and connected with the source of water supply and discharging into said rack and a substantially cone shaped fan mounted below said rack and rotatable therewith.

4. In a dish washing machine, a casing 125 open at its top end, a hinged closure for said top end, a spindle vertically and rotatably mounted in bearings on the under side of said closure and the bottom wall of said casing, a convex member rigidly mount- 130

ed on said spindle adjacent to the lower end thereof and carrying upwardly projecting blades, a dish rack rigidly mounted on said spindle above said convex member, and a
5 nozzle supported between said rack and said casing and connected with the source of water supply and discharging into said rack.

Signed at the city of Toronto, this ninth day of December, 1920.

RICHARD EDWARD CALLAHAN.
